UNITED STATES PATENT OFFICE.

WILLIAM A. GEIGER, OF CHICAGO, ILLINOIS, ASSIGNOR, BY MESNE ASSIGNMENTS, TO
W. H. MINER, INC., A CORPORATION OF DELAWARE.

RESILIENT SHACKLE.

Application filed September 19, 1923. Serial No. 663,684.

This invention relates to improvements in resilient shackles.

One object of the invention is to provide a simple and relatively inexpensive resilient 5 shackle adapted especially for use between mine cars and which is so arranged as to cushion both pulling and buffing shocks.

A more specific object of the invention is to provide a resilient shackle of the character 10 indicated, wherein are employed tandem arranged springs and the entire mechanism of compact form.

In the drawing forming a part of this 15 specification, Fig. 1 is a side elevational view of portions of two mine cars showing my improvements used in connection therewith. Fig. 2 is a horizontal, sectional view corresponding substantially to the section line 2—2 of Fig. 1. Fig. 3 is a vertical, trans- 20 verse, sectional view corresponding to the section line 3—3 of Figure 1. Fig. 4 is a detail perspective of one of the spring follower cages employed in my construction. Fig. 5 is an elevational view of one of the 25 intermediate followers employed with my construction. And Fig. 6 is a longitudinal, vertical, sectional view of the end portion of a mine car showing a modified form of connection for the shackle.

In said drawing, each of the mine cars is shown as having a heavy flooring 10, and end wall 11. Suitably rigidly secured to the heavy flooring of the car are two plates or 30 heavy straps 12 and 13, spaced at their outer or free ends to accommodate the ends of the shackle therebetween and which is adapted to be attached to said plates 12 and 13 by the usual coupling pins 14.

The improved shackle, as shown, 35 comprises, broadly, two spring followers A and B; two intermediate followers C and D; two springs E and F; two straps or yoke-acting arms G—G extending toward one mine car and two additional straps or yoke- 40 acting arms H—H adapted to be attached to the other mine car.

The two spring followers or cages A and B are of like construction and each is of 45 substantially rectangular outline with two opposite walls 15—15, two intermediate walls 16—16 and an integral end wall 17. The end walls 17 are adapted to act as the main end followers proper of the tandem gear, as will be understood. On the interior, 50 each of said followers A and B, has a cylind-

rical recess 18 adapted to accommodate and center one of the springs E or F, as the case may be. Each of the diametrically disposed walls 15 of each said main spring follower is extended beyond the intermediate walls 60 16 as indicated at 15^a in Figure 4. On the outer side of each of said extensions 15^a, a pair of laterally separated and overhanging flanges 19—19 are formed, leaving a somewhat T-shaped groove or recess 20 to accommodate one of the straps or yoke-acting arms G, as hereinafter described. The edges of the said extensions 15^a are beveled off as indicated at 21, the planes of said edges coinciding with two intersecting planes passing through the axis of the mechanism and arranged at 90° apart, as best illustrated in Figure 3. The two main followers A and B, when the parts are assembled, are turned relatively to each other through an angle of 75 90°. The amount of relative movement corresponds to the permissible compression of the springs E and F.

The two intermediate followers C and D are of like construction and each consists of a 80 disc-like plate 22 from which are extended, at diametrically opposite points, flaring wings 23—23, the edges 24 of said wings being in planes intersecting the axis of the mechanism and arranged at 90° to each other as in the case of the edges 21 of the main followers. With this construction, by arranging the two intermediate followers C and D at 90° apart, one of said followers will slide between the 85 extensions 15^a of one main follower and the other intermediate follower will slide between the extensions 15^a of the other main follower.

The two arms or straps G—G are of 90 like construction and each comprises a main strap section proper 25 having a T-shaped end 26 at one end and a flange 27 extending in a plane at right angles to the strap section proper 25. From the flange section 27 is extended a lug or wing 28 in a plane perpendicular to both of the planes defined by the flange 27 and main strap section 25. Each lug 28 is suitably apertured to accommodate a coupling pin 14 and it will be understood that the lugs 28 are each slightly 100 offset from the center line of the strap sections proper 25 so that the two lugs 28 overlap each other when the shackle is attached to a car.

The two straps or yoke-acting arms H are 110

also of like construction and each comprises a main strap section proper 125 having a T-head 126 at one end and a right angularly offset section 127 at its other end. From 5 the latter is extended a lug 128 suitably apertured to accommodate the other coupling pin when the shackle is attached to the car.

The T-head ends of the straps 25 are 10 engaged in the correspondingly shaped slots 20 of the main follower B and extended away from the latter so that the straps G will be secured to that car which is farthest from the main follower B. Similarly, the 15 T-headed ends of the straps H will be attached to the other main follower A, the opposite ends of said straps H being attached to that car which is farthest from the main follower A.

20 With the arrangement described, the operation is as follows, assuming a draft action and the righthand car remaining stationary, as viewed in Figure 1. As the left-hand mine car moves toward the left, the 25 straps H will be pulled thereby and the latter in turn will pull the main follower A in the same direction. During this action, the main follower B is held stationary by the straps G, said main follower B also 30 holding the intermediate follower D stationary since the latter is in engagement with the ends of the extensions 15^a. Movement of the follower A toward the left also produces a similar movement of the intermediate follower C, the wings of which are in 35 engagement with the ends of the extensions 15^a of said main follower A. In this manner, it will be evident that both springs E and F are simultaneously compressed. In a buffering action, and still assuming the righthand car remaining stationary, the main follower B will be moved toward the right, thus carrying with it the intermediate follower D. During this action, it is evident that the 40 main follower A will remain stationary and also the intermediate follower C held thereby. The two springs E and F are thus simultaneously compressed in the same manner as hereinbefore described. During the 45 buffering action described, the straps or arms G will remain stationary, the main follower B sliding with respect thereto. On account of the T-shape of the recess 20 which receives the arms G and H, the latter cannot 50 become disassembled with respect to the main followers to which they are attached. In actual practice, the length of the extensions 15^a of the main followers will be made such that the springs will be prevented from 55 over-compression by the intermediate follower D engaging the ends 16^a of the walls 16 of the follower A simultaneously with the wings of the intermediate follower C engaging the corresponding ends 16^a of the 60 walls 16 of the main follower B.

Referring next to the construction illustrated in Figure 6, 110 designates the heavy flooring of the mine car, and 112 a heavy strap secured to the flooring. The strap is provided with a forked end portion 149, 70 between the arms of which is pivotally mounted as by a horizontally disposed pin 150, the reduced end portion 151 of a connecting link 152. At the opposite end, the link 152 is horizontally slotted, thereby providing a pair of spaced arms 153 adapted to receive the lugs or wings 128' of the straps H' therebetween, the lugs 128' and arms 153 being perforated to receive the coupling pin 114, so that the parts are connected 80 for swinging movement in a horizontal plane.

It will be evident that the horizontal pivotal connection between the shackle and the strap 112 of the car permits of the shackle being swung in a vertical plane, upwardly or downwardly, when disconnected from the other car, to bring the shackle into a position where it will be out of the way when the car is being handled on the mine 90 hoist or in other places where the room is restricted.

From the preceding description, it will be seen that the tandem cushioning device 95 which I have provided is very compact; consists of few parts which may be relatively inexpensively manufactured; the springs are thoroughly protected from moisture and other deleterious action; the shackle will readily accommodate itself to pivotal movement when the cars are on curved sections 100 of track; and either end of the shackle may be attached to either car.

I have herein shown and described what I now consider the preferred manner of carrying out my invention, but the same is merely illustrative and I contemplate all changes and modifications that come within the scope of the claims appended hereto.

I claim:

1. In a resilient shackle, the combination with relatively movable casings; of tandem arranged yieldable units within said casings; followers interposed between said units, each of said followers being held by one of the casings and movable with respect to the other casing; oppositely arranged yokes adapted to be connected at their outer ends to adjacent vehicles, and each having its inner end connected to the casing remote from said yoke so as to permit movement of each yoke toward the casing to which it is connected and restrain relative movement with respect thereto in the opposite direction.

2. In a resilient shackle, the combination with aligned and relatively movable casings; of tandem arranged yieldable units within said casings; followers interposed between said yieldable units, each of said followers being adapted to abut against one of the 130

casings and being movable with reference to the other casing; oppositely arranged yokes having their adjacent ends connected to the casing remote from the body portion of the yoke, said connection permitting relative movement of each yoke toward the casing with which it is connected and restraining movement in the opposite direction.

3. In a resilient shackle, the combination with tandem arranged springs; of tandem arranged sets of main and intermediate followers, said main followers having follower-acting portions, and spacing portions extending therefrom for maintaining a predetermined distance between each follower-acting portion and the respective intermediate follower farthest therefrom; means for transmitting a pull from one main follower to a vehicle at one end of the shackle remote from said main follower; and means for transmitting a pull from the other main follower to another adjacent vehicle at the end of said shackle remote from said other main follower.

25 4. In a resilient shackle, the combination with tandem arranged springs; of tandem arranged sets of main and intermediate followers, each of said main followers comprising a follower-acting portion, and spacing portions for maintaining a predetermined distance between each follower-acting portion and the respective intermediate follower farthest therefrom; means for transmitting a pull from one main follower to a vehicle at one end of the shackle remote from said main follower; and means for transmitting a pull from the other main follower to another adjacent vehicle at the end of said shackle remote from said other main follower.

35 5. In a resilient shackle, the combination with tandem arranged springs; of tandem arranged sets of main and intermediate fol-

lowers; means for transmitting a pull from one main follower to a vehicle at one end of the shackle remote from said main follower; and means for transmitting a pull from the other main follower to another adjacent vehicle at the end of said shackle remote from said other main follower, each of said means comprising a yoke in the form of two separable bars.

6. In a resilient shackle, the combination with tandem arranged springs; of tandem arranged main and intermediate followers; means for maintaining a predetermined distance between each main follower and the respective intermediate follower farthest therefrom; yoke straps slidably connected with one of said main followers and extended beyond the other of the main followers and adapted to be attached to a vehicle; and yoke straps slidably connected to the second of the main followers and extended beyond the other main follower and adapted to be attached to a vehicle.

7. In a resilient shackle, the combination with a pair of followers; of resilient means co-acting with said followers; a yoke connected at one end to one of said followers and adapted to be attached at its other end to a vehicle; means arranged to effect compression of said resilient means upon movement of said followers in opposite directions; a second yoke connected at one end to the other of said followers; and means for connecting said last named yoke to an adjacent vehicle comprising a link secured to said last named vehicle for swinging movement in a vertical plane, said yoke being attached to said link for swinging movement in a horizontal plane, said shackle being movable as a unit to pendent position.

In witness that I claim the foregoing I have hereunto subscribed my name this 17th day of September, 1923.

WILLIAM A. GEIGER.
